CIGARETTE VENDING MACHINE

William H. Block, Chicago, Ill.

Application November 4, 1932, Serial No. 641,141

7 Claims. (Cl. 312—80)

My invention relates to cigarette vending machines, and more particularly to the means and method for procuring the delivery of the cigarettes, and my main object is to provide a machine by means of which the cigarettes may be delivered in single order without clogging or jamming in the machine.

A further object of the invention is to provide means for the support of the stock of cigarettes kept in the machine to relieve the cigarette to be delivered from the weight thereof.

A still further object of the invention is to provide a ledge which permits the free approach of the cigarettes to the delivery zone.

Another object of the invention is to construct the machine with means to check the fall of the stock of cigarettes kept in the machine in the direction of those cigarettes which change positions in the delivery zone, in order that such change may be unhindered.

An additional object of the invention is to construct the novel machine with few and simple parts which are of a sturdy nature, durable and inexpensive to manufacture.

With the above objects in view and any others that may suggest themselves from the specification and claims to follow, a better understanding of the invention may be had by reference to the accompanying drawing, in which

Fig. 1 is a plan view of the novel machine; and Fig. 2 is a vertical section on the line 2—2 of Fig. 1.

While machines for vending cigarettes and articles of a like character have been produced or under development for some time, I have been unable to find a machine particularly suited for the vending of cigarettes. This article is of a delicate nature, and may be deformed or crushed by light pressure, making it difficult to be fed or rolled for delivery, and also occasioning the dissipation or spilling of the tobacco contents. For machine vending purposes, the stock of cigarettes is carried in a carton, the bottom of which is opened when the carton is set upon the vending machine. Thus, the stock of cigarettes forms a load when the lowermost cigarettes are considered, and the difficulty has been to cause the movement and single delivery of the lowermost cigarettes without damaging effects by the load from above or the feeding device. In the novel machine, I have endeavored to overcome this difficulty by so designing the supporting and feeding means for the cigarettes that the ones in the zone of action will be free of compressing,

deforming, damaging, jamming or clogging tendencies.

In carrying out the above objects, specific reference to the drawing indicates that the machine is built upon a pyramidal base 10, which may be of cast metal and has a marginal shoulder 10a near the top to receive a super structure 11 which contains the supporting and delivery mechanism for the cigarettes. The structure 11 is in the nature of a cap in its lower portion which closely fits the top of the base 10. The form of the machine is preferably square, and the cap 11 receives a ring 12 which forms the seat for a glass container 13 into which the cigarette stock carton 14 is adapted to be fitted with the open end down. 70

The top of the base 10 has a pair of laterally spaced ribs 10b, the forward ends of these terminating upon a chute 10c into which the cigarette delivered falls to a point of easy access by the patron. The cap 11 is formed with side walls 11a, with a frontal wall 11b, which preferably recedes in an inward direction as indicated at 11c to form a lower section 11d, and a ceiling section 11e for the cap 11. 75

Between the ceiling section 11e and the ribs 10b is disposed a slide 15, which is preferably of light metal, such as aluminum. The slide has a vertical opening 15a in its forward portion and a short upstanding wall 15b behind the said opening. The portion in front of the opening has a depending lug 15c through which a V-shaped leaf spring 16 is passed whereby to be directed with its arms forwardly against the frontal wall of the cap 11, as indicated by dotted lines in Fig. 1, the ends of the spring being rounded back for a smooth contact with the frontal wall. The slide is then extended forwardly with a plunger 17 receiving a knob 18 at its outer end. 80

The nature of the spring 16 is such as to maintain the slide in the rearmost position indicated by full lines. The knob 18 is drawn forwardly when the delivery of a cigarette is desired to move the slide to the position indicated by dotted lines in Fig. 1. 95

The slide 15 is built up with a pair of laterally spaced intermediate walls 19 whose upper edges are inclined forwardly to meet the top of the wall 15b. The walls 19 are extended laterally with bearings 19a alongside of which are disposed arcuately shaped members 20, these being perforated for the loose passage of rivets 20a to hold the members 20 to the walls 19, and permit such members to be swung in a vertical plane between the full line and the dotted line positions indicated in Fig. 2. The rear portions of 100 105 110

the members 20 are also cut with oblique slots 20b to freely receive a rod 21 extending cross-wise between and secured to the walls 11a. The relation of the members 20 to the rod 21 is such 5 that when the members are carried forward by the assembly of the walls 19, the slots 20b will function as cams to swing the members 20 from the low full line position to the higher dotted line position.

- 10 The drawing indicates the machine in the inactive position, and shows by means of a group of circles such cigarettes as are in the bottom of the machine. Thus, the lowermost cigarette is indicated at A, the one next above by B, the 15 next behind by C, and so on. It will be apparent that a pull on the knob 18 to draw the slide 15 in forward direction will carry the cigarette A, which is at present resting upon the ribs 10b, to a position where it will fall off the same into 20 the chute 10c. The movement of the other cigarettes in the zone of delivery is very important as related to the movement of the slide and its associated parts in respect to the stock of cigarettes in the carton 14.

- 25 It is obvious that when the machine is at rest, the greater portion of the load in the carton 14 is borne by the internal walls 19 of the slide, and it follows that the inclined tops of these walls are intended to induce a forward movement of the 30 lowermost cigarettes in the carton as soon as an opportunity to permit such a movement occurs. Thus, as the slide moves through its forward stroke, it meets and lifts the cigarette B somewhat, the latter resting against the wall section 35 11d and under an inward ledge 11g formed therefrom. Thus, the cigarette B is held under the ledge and receives no pressure from above. The cigarette C is also lifted by the incline and progress of the walls 19, operating to push the 40 cigarette D in an upward and forward direction. Ordinarily, the next described action would be very difficult and attended by jamming because of the comparatively heavy load of cigarettes from above. However, during the forward 45 movement of the slide, the arcuate members 20 have progressed and swung upwardly whereby to act in scoop-like fashion to lift the load, starting with cigarettes F, G, H, etc. This action removes the pressure of the load from cigarettes 50 C and D permitting the free rolling and readjustment thereof. At the same time, the lifting action imposes enough forward pressure upon the cigarette E and others immediately above it to keep them above the ledge 11g and away 55 from the feeding zone. It is therefore seen that cigarettes C and D which would be otherwise subjected to crushing and packing influences either by the load or by the operation of any mechanism thereagainst are entirely relieved 60 when the load is lifted by the lifting members 20. Obviously, when the slide is permitted to recede, cigarette B falls into the space formerly occupied by cigarette A; cigarette C rolls under the ledge 11g; cigarette D falls into the space formerly occupied by the cigarette C, and so on. The zone in which the delivery occurs, is in the 65 nature of a V formed by the frontal wall section 11d and the tops of the internal slide walls 19, and it is seen that by the mechanism and operation described, I have eliminated the packing and crowding action which would otherwise occur in the lower portion of the V to the detriment of proper single delivery, so that I am 70 enabled to feed the cigarettes singly without 75 packing, deterring or deforming influences on

the part of the load and the mechanism. In addition, the lifting members 20 act as agitators for the superimposed load of cigarettes each time a delivery or return action occurs. Thus, what cigarettes may have a tendency to pack or crowd in the vicinity of the delivery mechanism are loosened by the action of the agitators. 80

In order that the cigarettes may be kept in proper condition, I have provided a receptacle 22 in the front wall formation of the cap 11, placing 85 a wet sponge 23 in the latter and making an opening 24 in the wall section 11d for the passage of the moisture into the cigarette compartment. The container 13 is made with an opening 13a opposite the receptacle 22 for the insertion or 90 removal of the sponge 23.

In conclusion, it is evident that I have provided a structure which is of few major parts—mostly of cast metal—making for the economical construction of the machine. Further, there are no delicate parts to get out of order or require adjustment, and the mechanism may be depended upon to operate for long periods without appreciable attention. 95

I claim:—

1. A cigarette vending machine, comprising a base, a receptacle above the same and adapted to receive a load of horizontally positioned cigarettes, a slide movable in forward direction with the effect of discharging the lowermost cigarette 105 in the frontal portion of the receptacle, scoop-like members actuated upwardly by the forward movement of the slide to boost the load above the zone of discharge, whereby to relieve the cigarettes below said load from the weight thereof, 110 and vertical supports upstanding from the slides, said members being pivotally attached alongside said supports.

2. The structure of claim 1, said members being slotted obliquely from their rear edges, and a rod 115 supported by the receptacle and passing transversely through the slots in the members, the angle of the slot being such as to impart a swinging movement in the upward direction as the slide moves forwardly. 120

3. A vending machine comprising a receptacle for horizontally-stacked cigarettes, a support in the bottom of the receptacle, a slide operable over the support and perforated to admit a cigarette upon the latter, the forward movement of the slide dislodging the cigarette from the support for discharge, means leading next succeeding cigarettes in the stack in the direction of the one disposed for discharge, and elements co-acting at the time of discharge to isolate such succeeding 125 cigarettes from the remainder in the stack, said elements comprising a projection inwardly from the front wall of the receptacle and lifting members opposite the projection, the lifting members being carried by the slide, and a connection actuating the lifting members on the forward movement of the slide. 130

4. The structure of claim 3, said lifting members being pivoted to the slide, and a connection actuating the lifting members on the forward 140 movement of the slide.

5. A vending machine comprising a receptacle for horizontally-stacked cigarettes, a support in the bottom of the receptacle, a slide operable over the support and perforated to admit a cigarette 145 upon the latter, the forward movement of the slide dislodging the cigarette from the support for discharge, means leading next succeeding cigarettes in the stack in the direction of the one disposed for discharge, and elements co- 150

- acting at the time of discharge to isolate such succeeding cigarettes from the remainder in the stack, said elements comprising a projection inwardly from the front wall of the receptacle and 5 lifting members opposite the projection, the lifting members extending forwardly and pivoted with their rear portions to the slide, and a connection actuating the lifting members on the forward movement of the slide. 80
- 10 6. A vending machine comprising a receptacle for horizontally-stacked cigarettes, a support in the bottom of the receptacle, a slide operable over the support and perforated to admit a cigarette upon the latter, the forward movement of 15 the slide dislodging the cigarette from the support for discharge, means leading next succeeding cigarettes in the stack in the direction of the one disposed for discharge, and elements co-acting at the time of discharge to isolate such 20 succeeding cigarettes from the remainder in the stack, said elements comprising a projection inwardly from the front wall of the receptacle and lifting members opposite the projection, the lift- 95

- ing members being pivoted to the slide, extensions of the members beyond the pivots, a stationary element, and a connection between the extensions and the stationary element operative to actuate the lifting members on the forward movement of the slide. 85
7. A cigarette vending machine, comprising a base, a receptacle above the same and adapted to receive a load of horizontally positioned cigarettes, a slide movable in forward direction with the effect of discharging the lowermost cigarette in the frontal portion of the receptacle, scoop-like members actuated upwardly by the forward movement of the slide to boost the load above the zone of discharge, whereby to relieve the cigarettes below said load from the weight thereof, and forwardly-inclined supports upstanding from the slide to lead the lowermost cigarettes in forward direction toward the zone of discharge, said members being pivotally attached to the supports. 90
